United States Patent Office

Des. 207,584
Patented May 9, 1967

207,584

DRAPERY ROD FINIAL

Kenneth M. Johnson, Kensington, and Kieran D. Doyle,
Wallingford, Conn., assignors to The Stanley Works,
New Britain, Conn., a corporation of Connecticut

Filed Nov. 22, 1966, Ser. No. 4,770

Term of patent 14 years

(Cl. D21—1)

fig. 1

fig. 2

FIG. 1 is a front elevational view of a drapery rod finial embodying our new design; and

FIG. 2 is an end view thereof.

The fragmentary broken line showing of a drapery rod in FIG. 1 is for illustrative purposes only.

We claim:

The ornamental design for a drapery rod finial, as shown and described.
